ENDLESS TRACK AND DRIVE TRANS-
MISSION THEREFORWilliam H. Pethick, Regina, Saskatchewan,
Canada

Application December 7, 1944, Serial No. 567,070

1 Claim. (Cl. 180—9.1)

1

My invention relates to improvements in the driving means for endless track tractors, and in improvements of the suspension of the chassis thereof, an object of this invention being to provide a device of the character herewithin described in which the power plant distributes a tractive effort to four points approximately at the four corners of the unit, the unit or tractor embodying a chassis and a pair of vertically resilient or yieldable supporting assemblies on either side of the chassis each independent of the other so that they may follow the ground contour without transmitting torsion or stress to the chassis, which may therefore be considered in "floating" suspension between the assemblies aforesaid.

A further object of my invention is to provide a device of the character herewithin described in which the draw-bar is attached in the approximate centre of the unit thereby eliminating any tendency of the front end to rise when exerting a tractive effort.

A further object of my invention is to provide a device of the character herewithin described which is susceptible to being V-belt driven thereby effecting a considerable saving in weight, metal and cost of machining.

A further object of my invention is to provide a device of the character herewithin described, by which, in view of the four-point distribution of the tractive effort will effect a considerable economy in gasoline consumption.

A further object of my invention is to provide a device of the character herewithin described wherein the crawler track, being carried dynamically at the front and rear ends will give longer service without repair through considerable reduction in the wear of the track pins and bushings.

A further object of my invention is to provide a device of the character herewithin described, in which the power, being distributed by means of V-belts, will provide a certain percentage of slippage between the power plant and the track carriers which will serve to cushion or damp-down sudden shocks, thereby also greatly reducing wear upon the track itself and particularly the pins and bushings thereof, but in addition, reducing wear upon such parts as the engine wrist pins.

A further object of my invention is to provide a device of the character herewithin described, which, due to the provision of V-belts between the power plant and the endless track carriers will develop power gradually under heavy load

2

and on slippery ground, thereby greatly aiding the tractive efficiency of the unit under such conditions in contrast to the sudden application of tractive effort when transmitted to gears which takes place in conventional endless track drives, and which so frequently disturbs footing in slippery conditions.

A further object of my invention is to provide a device of the character herewithin described in which the floating chassis should materially reduce the incidence of accidents mainly due to being thrown from the machine, and in addition the onset of dislocations, strains and sprains, but particularly kidney trouble which so often develops in endless track tractor operators after a sustained period of operation of these vehicles.

A further object of my invention is to provide a device of the character herewithin described in which the drive shaft or central axle being so closely adjacent to the ground and in such close proximity to the track idler rollers, provides an ideal gun-carriage when my invention is used as an instrument of war, since the use of jacks and tedious adjusting could be eliminated before firing.

A further object of my invention is to provide a device of the character herewithin described in which the two endless tracks, being able independently to follow the ground contour will materially increase the possible speed potentialities of a unit fitted with my invention over soft and rough ground.

A further object of my invention is to provide a device of the character herewithin described in which the main drive shaft is susceptible to the well known knee-action type of mounting, which lends itself particularly to the resilient V-belt which I employ. With such a form of mounting for the drive shaft, the high speed potentialities of a unit built according to my invention would be greatly increased.

A further object of my invention is to provide a device of the character herewithin described which could be manufactured at a particularly low cost, the belt-casings, by which I mean the elongated structural members enclosing the belt, being manufactured of boiler plate, with the driven pulleys adjacent the track sprockets of skeleton cast iron configuration and the like.

A further object of my invention is to provide a device of the character herewithin described which in addition to being of low manufacturing cost would also be particularly easy and simple to service in contrast to prevailing types of endless track tractor.

With the foregoing objects, in view, and such other objects and advantages as will become apparent to those skilled in the art to which this invention relates as this specification proceeds, my invention consists essentially in the arrangement and construction of parts all as hereinafter more particularly described, reference being had to the accompanying drawings, in which:

Figure 1 is a side elevation partly in section illustrating my invention in association with a combat tank superstructure.

Figure 2 is an enlarged detail on the line 2—2 of Figure 3.

Figure 3 is a plan view of my invention incorporated with a combat tank superstructure, the same showing one of my four-point connections in situ and in plan with the superstructure broken away, and also illustrating one of my track carrying or chassis supporting assemblies with the crawler track removed therefrom.

In the drawings like characters of reference indicate corresponding parts in the different figures.

In the accompanying drawings I have shown a combat tank superstructure 1 as being mounted upon the chassis 2, which chassis, it is to be understood, may be of any configuration or size according to the purpose for which the unit is intended when manufactured. Extending along the two parallel sides of the chassis and adjacent thereto are my track carrying chassis supporting assemblies collectively designated 3.

The track carrying or chassis supporting assemblies 3 each consist of a pair of spaced, parallel and elongated structural members 4 and 5, these members being in the form of vertically disposed plates of the configuration clearly indicated in Figure 1, and extending between each of the two members of each pair at the front and rear ends thereof are stub shafts 6 journaled in the said members and projecting therebeyond, said shafts supporting, at the other ends thereof and adjacent to the external surfaces of the members 4 and 5, the track carrying sprocket wheels 7.

Also positioned upon the stub shafts 6 and coaxial with the sprocket wheels 7 between each pair of plates 4 and 5 are the belt driven rollers 8, these members being keyed to the shafts 6 for the rotation thereof. These rollers are grooved to receive the V-belts 9, the opposite ends of these belts passing around a drive roller 10 keyed to each of the projecting ends of a drive shaft 11 which lies horizontally and parallel to the axis of rotation of the sprocket wheels 7, between the front and rear pairs thereof, the said drive shaft 11 being rotated by means of a power plant 12 positioned approximately centrally of the chassis 2.

Around the sprocket wheels extend the tracks 13, being supported upon conventional rollers 14 extending between the plates 4 and 5, and from the foregoing it will be seen that I have provided means whereby tractive effort may be applied at the front and rear ends of each caterpillar track since those belts 9 which extend forwardly to engage the front rollers 8 will transmit tractive effort to the front sprocket wheels, while those belts similarly enumerated which extend rearwardly to the hind rollers will transmit tractive effort to the adjacent rear sprocket wheels in the same direction.

The chassis 2 is supported on the track carrying or chassis supporting assemblies which I have just described at the four points 15, the details of the resilient connections between chassis and assembly at these points being best illustrated

in Figure 2 wherein it will be seen that I provide vertical recesses 16 in the sides of the chassis through the top and bottom ends 17 of which extends a rod 18. Projecting inwardly from the opposing surfaces of each of the inner plates 5 is a heavy bracket or lug 19 suitably stiffened by the portions 20, the lug 19 being provided with the aperture 21 so that the rod 18 may extend therethrough.

Upper and lower coil springs 22 and 23 extend between the opposite surfaces of the lug and the upper and lower ends of the recess 16 so that normally, it will clearly be recognized that the chassis 2 is directly supported via the springs 22 resting upon the upper surface of the lugs 19. However, it will also be recognized that by the yieldable or floating connection or suspension which I have just described, each of the track carrying or chassis supporting assemblies 3 is free to yield in a vertical plane about the drive shaft 11 independently of the chassis and independently of the other assembly as indicated by the dotted lines 24 in Figure 1.

Finally it is to be noted that my draw-bar 25 is connected to the drive shaft 11, as by means of the roller bearing mounted collars 26 or by any other mechanical expedient, and by this connection, it is apparent that I achieve the objects already set forth in the preamble to this specification.

Since various modifications can be made in my invention as hereinabove described, and many apparently widely different embodiments of same made within the spirit and scope of the claim without departing from such spirit and scope, it is intended that all matter contained in the accompanying specification shall be interpreted as illustrative only and not in a limiting sense.

What I claim as my invention is:

An endless track drive comprising in combination with a chassis, four front and rear pairs of spaced, track carrying sprocket wheels, each pair having a belt driven wheel therebetween co-axial to and secured in rotary connection therewith, said pairs of track carrying sprocket wheels being positioned adjacent each corner of said chassis, a drive shaft parallel with the axis of rotation of said pairs of sprocket wheels, said drive shaft being positioned between the front and rear pairs of sprocket wheels, a multi-belt drive wheel on each end of said shaft in rotary alignment with the front and rear track carrying sprocket wheels upon each side of said chassis, and at least two belts around each of said drive wheels one extending forwardly and the other rearwardly around said driven wheels respectively, to provide a four-point drive for said track.
